UNITED STATES PATENT OFFICE.

FRIEDRICH EICHE, OF SCHANDAU, SAXONY, GERMANY.

KEY-HOLE GUARD.

SPECIFICATION forming part of Letters Patent No. 410,506, dated September 3, 1889.

Application filed August 8, 1888. Serial No. 282,263. (No model.)

To all whom it may concern:

Be it known that I, FRIEDRICH EICHE, dentist, a subject of the Emperor of Germany, residing at Schandau-Sachsenburg, in the Empire of Germany, have invented certain new and useful Improved Closing Devices for Key-Holes of Locks, of which the following is a specification.

The object of the present invention is to provide locks with a safety-closing device, which will effectually prevent them from being picked or opened after being locked and the key withdrawn.

Most locks, and especially those manufactured wholesale, with tubular keys or keys with solid shanks, can be unlocked with more or less difficulty with master keys or picked with skeleton keys, hooks, and the like, and offer, therefore, little security against burglary and theft. By this invention, however, each lock can be secured against being picked, by the introduction into the key-hole of a safety closing device, which is adjusted by a small key (kept by the owner) in such a manner that it cannot be moved without the help of this small key. The form of this small key is different for every lock and is intended to be kept secret by the owner. The form of the device also differs for locks with tubular keys from those with keys having solid shanks.

In the accompanying drawings, Figures 1 and 2 represent the ordinary solid-shanked key in the lock. Figs. 3 and 4 represent a closing device for locks with keys having such solid shanks. Figs. 5 and 6 represent the different parts of this closing device. Figs. 7, 8, and 9 are cross-sections of the sleeve shown in Fig. 6 on lines I, II, III, IV, and V VI, respectively. Figs. 10 and 11 represent small pinchers for introducing and withdrawing the closing device. Figs. 12, 13, and 14 represent a closing device for locks and keys having solid shanks in plan, front elevation and section, respectively. Figs. 15 to 17 represent a similar device with a modification.

The closing devices for locks with keys having solid shanks consist of a sleeve, Fig. 6, formed with transverse slots B and M, and in which turns a core or plug K', provided with the key-bit B' and a pin M', as shown at Fig.

5. The plugs or cores K' are adapted to turn in the tubes H, so that the key-bit B' may be turned in order to engage with the inner wall of the lock. After the closing device has been introduced the tube H does not turn in the key-hole. To this end the tube H is formed with the two before-mentioned transverse slots B and M, the former, Fig. 8, for the key-bit B', the latter, Fig. 7, for the pin M', which is fixed into the core after the latter is introduced in the tube for the purpose of holding it in the tube. This pin may, however, be omitted if the longitudinal slot for the introduction of the key-bit is afterward closed. The core and tube are removed from the key-hole by the small pinchers Z' Z², or the small keys Z³ Z⁴, Figs. 12 and 17, after the core K' has been turned, so that its key-bit B' registers with the key-hole.

The removal of the closing device from the lock is only to be effected by the owner, and therefore an instrument different in form for each lock is used. This instrument may be in the form of pinchers Z', Fig. 10, which are pushed over the projection C of the core K' and engage with two teeth or pins in the said projection; or the instrument may be in the form of a pair of extending levers Z², pivoted together, Fig. 11, for which the core K² must be formed with recess A and transverse holes. Instead of these instruments, a small key may be used, which engages with the core or the tube of the closing device. Fig. 17 represents such a key, which would fit the devices represented in Figs. 15 and 16 and engage the core K².

The key Z³ ends in a small projection of any desired section and provided with a small key-bit b. This projection fits in an opening in the core or tube. The key-bit is turned in a transverse slot in this opening, and thus the core or tube can be turned and extracted from the key-hole of the lock. The small key Z⁴, Figs. 12 and 13, is also provided with a projection for turning the core, but has no key-bit. Instead of the latter, the bow of the key is in the form of a spring with a hook h at the end, which is pressed over a projection of the tube H⁴ and engages with this projection, when the closing device may be withdrawn.

When the lock is locked and the key with-

drawn, the closing device is introduced in the key-hole and the key-bit is turned, so that it engages with the inner wall of the lock. The small turning instrument or key is then withdrawn until it is introduced again for the purpose of withdrawing the closing device.

Having now particularly described and ascertained the nature of my said invention and in what manner the same is to be performed, I declare that what I claim is—

A removable key-hole guard consisting, essentially, of a sleeve having a pair of peripheral slots extending partially around the same, and a core loosely located and adapted

to rotate in said sleeve and provided with a pin extending through one of said slots and with a key-bit extending through the other slot, the outer end of the core being formed to receive a key to turn the same, substantially as described.

In testimony whereof I have hereto set my hand in the presence of two subscribing witnesses.

FRIEDRICH EICHE.
